UNITED STATES PATENT OFFICE

152,521

DESIGN FOR A TRAY

Naomi Mae Dean, Auxvasse, Mo.

Application May 28, 1947, Serial No. 139,331

Term of patent 14 years

(Cl. D44—10)

To all whom it may concern:

Be it known that I, Naomi Mae Dean, a citizen of the United States, residing at Auxvasse, in the county of Callaway and State of Missouri, have invented a new, original, and ornamental Design for Trays, of which the following is a specification, reference being had to the accompanying drawings forming part thereof.

In the drawings:

Figure 1 is a front elevation of a tray showing my new design;

Figure 2 is a side elevation; and

Figure 3 is a perspective view thereof.

I claim.

The ornamental design for a tray, as shown.

NAOMI MAE DEAN.
